CLAIM

The ornamental design for an oven mitt, as shown and described.

DESCRIPTION

FIG. 1 is a front view of the present invention.

FIG. 2 is a right side elevation view of FIG. 1.

FIG. 3 is a top view of FIG. 1.

FIG. 4 is a bottom view of FIG. 1.

FIG. 5 is a left side elevation view of FIG. 1.

FIG. 6 is a rear view of FIG. 1.

FIG. 7 is a front view of a related embodiment of the invention in FIG. 1.

FIG. 8 is a right side elevation view of the embodiment in FIG. 7.

FIG. 9 is a top view of the embodiment in FIG. 7.

FIG. 10 is a bottom view of the embodiment in FIG. 7.

FIG. 11 is a left side elevation view of the embodiment in FIG. 7; and,

FIG. 12 is a rear view of the embodiment in FIG. 7.

Items shown in phantom-lines in FIGS. 1 to 12, are for illustrative purposes only to reflect the environment of the inventive design, and do not constitute a part of the claimed design.
